UNITED STATES PATENT OFFICE.

FRANK A. GURLEY, OF MERIDIAN, MISSISSIPPI.

DESIGN FOR A BACK-BAND HOOK.

SPECIFICATION forming part of Design No. 28,348, dated March 8, 1898.

Application filed January 31, 1898. Serial No. 668,677. Term of patent 14 years.

To all whom it may concern:

Be it known that I, FRANK A. GURLEY, a citizen of the United States, residing at Meridian, in the county of Lauderdale and State 5 of Mississippi, have invented a new and original Design for a Back-Band Hook, of which the following is a specification.

This invention relates to a new and original design for a back-band hook; and it has 10 for its object to provide a design of this character that shall be both useful and ornamental.

The leading feature of the design resides in a base-plate provided with a triangular 15 group of offstanding rounded peripheral ears and having a circular opening therein surrounded by a forwardly-projecting circular flange cut away at one side, said base-plate also having at one edge a U-shaped hook portion provided with an outer straight arm lying 20 parallel to the body of the plate and having its extremity projected through said cut-away portion of the flange within the plane of the latter.

25 A minor feature of the design is the peripheral lugs having circular openings therein, and the outer straight arm of the U-shaped hook portion being provided at its extremity with an inturned right angularly-disposed 30 lug projection.

In the drawings, Figure 1 is a perspective view of a back-band hook embodying the herein-described design. Fig. 2 is a plan view thereof. Fig. 3 is a cross-sectional view on the line 3 3 of Fig. 2.

35

Referring to the accompanying drawings, the numeral 1 designates a base-plate of a circular form having a triangular group of offstanding rounded peripheral ears 2, provided therein with circular openings 3. The 40 said base-plate is further provided with a circular opening therein surrounded by a forwardly-projecting circular flange 4, which flange is cut away at one side, as at 5. Below the cut-away portion 5 of the flange 4 the 45 base-plate is extended into a U-shaped hook portion 6, having an outer straight arm extended through said cut-away portion 5, and provided at its terminal with an inturned right angularly-disposed lug projection 7. 50

What is claimed is—

The design for a back-band hook, herein shown and described.

In testimony that I claim the foregoing as my own I have hereto affixed my signature in 55 the presence of two witnesses.

FRANK A. GURLEY.
